Primary Examiner — Susan Moon Lee(74) *Attorney, Agent, or Firm* — Epstein Drangel LLP; Robert L. Epstein(57) **CLAIM**

The ornamental design for eyewear, substantially as shown and described.

DESCRIPTION

FIG. 1 is a front, top isometric view of my design for eyewear. FIG. 2 is an isometric view showing the rear and top of my design;

FIG. 3 is a plan view showing the front of my design;

FIG. 4 is a plan view showing the back of my design;

FIG. 5 is a plan view showing one side of my design, the other side being the mirror image thereof;

FIG. 6 is a plan view showing of the top of my design; and,

FIG. 7 is a plan view showing the bottom of my design.

1 Claim, 5 Drawing Sheets# US D747,401 S
